UNITED STATES PATENT OFFICE.

CHARLES E. MILLER, OF PITTSBURGH, PENNSYLVANIA.

SUPPORTING-BRACKET.

1,385,638.

Specification of Letters Patent. Patented July 26, 1921.

Application filed January 25, 1918. Serial No. 213,806.

To all whom it may concern:

Be it known that I, CHARLES E. MILLER, a citizen of the United States, and a resident of Pittsburgh, in the county of Allegheny and State of Pennsylvania, have made a new and useful Invention in Supporting-Brackets, of which the following is a specification.

This invention relates to supporting brackets or devices and more particularly to 10 insulator supports.

It is now common to make up insulator supporting brackets from standard metal shapes or sheets. In certain types it is desirable to secure the same to the mounting 15 element (a pole or side of a building) by means of a single screw (either a wood screw, a lag screw or a bolt) and various schemes have been devised and tried out for providing the bracket or arm with such a screw or 20 bolt. In making up such brackets or supporting devices it is desirable to use standard shapes such as channel sections and plates or sheets and considerable difficulty has been experienced in providing brackets 25 made from standard shapes with a suitable screw or bolt.

An object of this invention is to provide simple and efficient means for rigidly securing a screw or bolt of standard pattern to a 30 supporting arm or other fixture.

A further object is to produce an insulator support, made up of standard material and having a standard screw or bolt as an element thereof.

35 A still further object is to provide simple and efficient means for rigidly securing together a supporting arm, a base or fulcrum plate and a screw or bolt to form a relatively cheap supporting bracket or device.

40 These as well as other objects which will readily appear to those skilled in this particular art I attain in the devices illustrated in the drawings accompanying and forming a part of this application.

45 In the drawings, Figure 1 is a view in side elevation of an insulator support embodying this invention, Fig. 2 is a view in sectional elevation of the same and Fig. 3 is a view separately showing in perspective the 50 three elements entering into the make up of the support. Fig. 3^a is a view in perspective of a screw and illustrates the manner of treating the same for use with supporting arms made from relatively thin 55 stock. Fig. 4 is a view in side elevation of another type of insulator supporting bracket

made in accordance with this invention. Fig. 5 is a front view in elevation of the same. Fig. 6 is a view in section taken on line 6—6 of Fig. 4 and Fig. 7 is a view in 60 sectional elevation of another form of supporting device embodying this invention.

This invention is applicable to a great variety of devices and for the purpose of illustration but with no idea of limiting it I 65 have shown it applied to three types of supports.

The device shown in Figs. 1, 2 and 3 consists of a supporting arm 8 struck from a standard channel section, a base or fulcrum 70 plate 9 stamped from sheet metal and a standard wood screw 10 the head of which has been squared. In order to rigidly secure the three elements together the base of the channel is punched or cut away leaving the ends of the sides 11 and 11^a to serve as tenons, the channel base being also punched to provide a slot conforming to the squared head portion 12 and adjacent shank portion 13 of a standard screw. This it will 75 be understood may either be a wood screw, a lag screw, or any desired form of bolt.

The screw is inserted in the slot made for its reception in the channel base and on account of its head portion being squared is 80 prevented from turning in the slot. The 85 base or fulcrum plate 9 is punched with three holes 14, 15, 15^a. Hole 14 is of a size and shape to snugly fit the upper shank portion of the screw and the slots or holes 15, 15^a of 90 a size to fit the tenons 11, 11^a. After the screw is assembled in the supporting arm the base plate is slipped over the screw (the shape of which is preferably tapered), the tenons projecting through holes 15, 15^a beyond the base plate and the screw projecting 95 through the center 14. The tenons are then riveted over and the structure is thus completed. For the purpose of insuring that the screw shall be rigid with respect to the 100 support arm its head is preferably clenched to the support as shown. The base plate centers the screw with relation to the support arm and since the screw is rigidly held in the arm and the plate is riveted to the arm 105 a rigid structure is produced. The base plate is preferably provided with two holes 16 and 16^a so that screws or nails may be used for preventing the support from turning when in place.

In Figs. 4, 5 and 6 I have shown an insulator support having a curved arm and

which embodies this invention. The curved arm 17 is struck from a channel section and is punched so as to provide tenons 11 and 11^a and a slot for the reception of the screw. Base plate 9, arm 17 and the screw are secured together in the manner above described with relation to Figs. 1 to 3.

In Fig. 7 I have shown a supporting member having an eye piece 18 punched from sheet metal and provided with an eye 19, a slot for the reception of screw 10 and the tenons 11, 11^a. Eye piece 18, the base and the screw are secured together in the manner described with relation to Figs. 1 to 3.

Having thus described my invention what I claim is—

1. A support member slotted to receive the head portion of a screw, a screw the head of which lies within said slot, a fulcrum member secured to one end of the support member and provided with a hole through which said screw projects and means for securing said fulcrum member to said support.

2. A support member slotted to receive the head portion of a screw, a screw the head of which lies within said slot and is clenched to said member, and a member secured to one end of the support member and provided with a hole through which said screw projects.

3. A support member slotted to receive the head portion of a screw, a screw the head of which lies within said slot and which is clenched to said support member, and a washer pierced to receive said screw and riveted to the end of said support member.

4. A support member slotted to receive the head portion of a threaded securing element, a threaded element having an enlarged head lying within said slot, and an alining member pierced to receive said threaded member and riveted to the end of said support member.

5. A support member slotted to receive the head portion of a threaded securing element, a threaded element having an enlarged head lying within said slot and having its head portion clenched to said support member and an alining member pierced to receive said threaded member and riveted to the end of said support member.

6. An insulator support comprising a support arm slotted to receive the head portion of a screw, a screw the head of which lies within said slot, and a base plate pierced to receive said screw and riveted to the end of said arm.

7. An insulator support comprising a support arm slotted to receive the squared head portion of a screw, a screw the head of

which lies within said slot and which is clenched to said arm, and a base plate pierced to receive said screw and riveted to the end of said arm.

8. An insulator support, comprising a support arm slotted to receive the head portion of a screw and to provide tenons, a screw the head of which lies within said slot, and an abutment member pierced to receive said screw and tenons and which is secured to said arm by means of said tenons.

9. An insulator support, comprising a support arm slotted to receive the head portion of a screw and to provide tenons, a screw the head of which lies within said slot and which is clenched to said arm, and an abutment member pierced to receive said screw and tenons and which is secured to said arm by means of said tenons.

10. An insulator support, comprising a support arm, a base plate and a screw: the arm being formed of channel section punched at one end to receive the head and upper shank portion of said screw and to provide tenons, the base plate being pierced to receive said screw and said tenons, the screw head being up set to clench the arm and the tenons being deformed so as to lock said base plate to the end of said arm.

11. An insulator support comprising a base plate, a screw passing through said plate and having its head spaced therefrom, and a support arm having one end secured to said plate and having a slot spaced from said end embracing the head of said screw whereby alinement of said screw and said arm is maintained.

12. An insulator support comprising a base member, a screw passing through said member and provided with a polygonal head, and a support arm secured to said member and provided with a slot to receive the polygonal head on said screw the diagonal of said head being greater than the greatest width of said slot whereby relative rotation of said screw and said arm is prevented.

13. An insulator support comprising a base member a screw passing through said member and provided with a head having opposite flat portions on its circumference and a support arm secured to said member and provided with a slot to receive the head on said screw the diagonal of said head being greater than the width of said slot whereby relative rotation of said screw and said arm is prevented.

In testimony whereof, I have hereunto subscribed my name this ninth day of January, 1918.

CHARLES E. MILLER.
